UNITED STATES PATENT OFFICE.

HARRY J. TAYLOR, OF BURLINGTON, NEW JERSEY.

PIPE-MOLDING MACHINE.

SPECIFICATION forming part of Letters Patent No. 645,498, dated March 13, 1900.

Application filed April 15, 1899. Serial No. 713,189. (No model.)

To all whom it may concern:

Be it known that I, HARRY J. TAYLOR, a citizen of the United States, residing at Burlington, in the county of Burlington and State of New Jersey, have invented certain new and useful Improvements in Pipe - Molding Machines; and I do hereby declare the following to be a full, clear, and exact description of the invention, such as will enable others skilled in the art to which it appertains to make and use the same.

This invention relates to machines for packing or ramming sand to form molds for casting pipes.

15 My object is the provision of an improved machine for forming the mold in which the pipe is to be cast which will automatically feed and distribute the sand evenly in the flask around the pattern and pack or ram it 20 firmly and evenly at all points, so that the mold will be built rapidly and properly rigid when the pattern is withdrawn.

25 The invention embodies novel means for distributing and feeding the sand, whereby choking or clogging is prevented and improved automatic packing or ramming devices and operating mechanisms, as well as other improved features, all of which are set forth in detail hereinafter, and particularly 30 pointed out in the appended claims.

35 In the accompanying drawings, Figure 1 is a front elevation of the machine; Fig. 2, a side elevation; Fig. 3, a cross-section of the slide and casing; Fig. 4, a vertical section of the same; Fig. 5, a vertical section of the flask, pattern, and sand-box; Fig. 6, a detail plan of the lifting-box and adjacent devices, and Fig. 7 a detail side elevation of the same.

40 The frame 1, which carries the different mechanisms, is provided with pivots 1^a, journaled in fixed beams 1^b, at its top and bottom, so that it can be swung on a vertical axis. There are two horizontal rotary tables 2, having gear-teeth on their peripheries, which 45 mesh with the teeth of a pinion 3, which drives them. This pinion is turned by a vertical shaft 4, suitably geared to a horizontal shaft 5, which is operated from a power-shaft 6 by chain-and-sprocket gearing. A band-pulley 50 6^a on shaft 6 affords means for driving the shaft. A tappet-shaft 7 is operated by the power-shaft through the intervention of a gear

8, which it carries, and a pinion 9 on the power-shaft. The power-shaft also carries a pinion 10.

55 In the present machine two duplicate sets of mechanisms are employed, so that the molds for two pipes may be formed or rammed simultaneously, and the following description is applicable to both sets of mechanisms.

60 The numeral 11 designates a vertical guide-casing connected to the frame and having guides or tracks 12, extending from top to bottom on opposite sides, and a guide-slot 13 in its front. Within the casing is a slide 14, having a rack 15 extending along its back throughout its length. This slide is of approximately the length of the casing and adapted to travel therein from end to end. It is provided with a bracket 16, which projects through and 70 travels in the slot 13, thus assisting in guiding and steadyng the slide during its movements. A hollow packing or ramming cylinder 17 is rigidly hung from the bracket in parallel disposition relatively of the slide and 75 casing, and at the bottom of the cylinder are the rammer-bits 18, which are hinged, as shown at 19, which insures a perfectly regular and even ramming of the end of the mold. Straight rigid bits could be substituted, if 80 desired, when ramming the straight part of the mold. These bits are connected to the bottom of the ramming-cylinder at short distances apart, which insures a ramming of 85 every part of the mold.

At the upper end of the casing 11 are wheels or sheaves 20, over which pass chains 21, connected at one end to the slide 14 and at the other end to counterbalancing weights 22, which slide in the tracks or guides 12. These 90 weights are sufficiently heavy to balance the slide, the weight of the ramming-cylinder being sufficient to pack the sand to the desired degree of firmness.

95 The numeral 23 designates a windlass, which is geared to pinion 10 in such manner that it can be thrown in and out of gear as desired. A chain 24, running over a sheave at the top of the casing, connects this windlass with the slide, so that the latter and the ramming 100 mechanism can be raised or lowered with ease when desired. The tappet-shaft 7 carries a wheel having tappets 7^b, provided with anti-friction-rollers at their ends to reduce the

- wear on themselves and the lifting-box 25. The lifting-box is movable vertically in suitable guides 26 and has a cam-track 27 on its lower end, against which the wheels on the 5 tappets strike and travel. A pawl 28, pivoted to the lifting-box at 29, is adapted to engage the rack and lift the slide when the lifting-box is raised by the tappet, and the toe of this pawl is sustained by a stud or block 30.
- 10 The heel 31 of the pawl is in position to engage a trip 32 on the frame 1 when the lifting-box has been raised sufficiently, which disengages the toe of the pawl from the rack, allowing the rammer and slide to drop by 15 gravity. A stop 33 is provided on the lifting-box to limit the movement of the heel of the pawl when tripped by the part 32. On the lifting-box is a catch 34, and on the frame 1 is a pivotally-mounted sustaining-catch 35, 20 adapted to be swung under the catch 34 to support the box in inoperative position when the mold has been completed on one side of the machine and the other mold is not finished.
- 25 Supported, end on, on the rotary table 2 is a flask 36, of usual construction, and within this is the pattern 37, which has a hub 38 at its lower end, of proper shape to form the mold for the outer part of the hub of the pipe.
- 30 The numeral 39 designates a sand-box, of cylindrical shape and the same diameter as the pattern, which has a bottom 40 separated from the sides of the box by a space 41, through which the sand is fed. This box has 35 legs 42, which fit in pockets 43 in the upper end of the pattern, supporting the box with its bottom sufficiently far above the pattern to give ample space for the discharge of the sand into the space 44, between the flask and pattern, where the mold is rammed. To prevent choking or clogging of the sand, I provide an agitator 45, which comprises a straight bar 46 of the same length as the diameter of the bottom, having a pivot 47, which fits 40 loosely in a pocket in said bottom, a vertical shaft 48, rising from the center of the box, and inclined bracing and agitating rods 49, rising from the bar to the shaft on opposite sides of the latter. The shaft 48 is secured 45 to casing 11 by a bracket 50.
- 50 The flask, pattern, sand-box, and agitator having been placed in position, the pawl is released from the rack and the windlass operated to lower the ramming-cylinder into the flask and around the pattern. The pawl being reengaged with the rack and the machine set in motion, the operation will be as follows: The table turns with the flask, pattern, and sand-box, while the agitator is stationary.
- 55 The sand is stirred by the agitator and issues in a continuous stream from all parts of the space at the bottom of the sand-box, enveloping the upper end of the pattern on all sides and falling into the space 44. As the 60 tappets revolve their rollers strike the cam on the lifting-box, and while traveling over it raise the box steadily higher and higher

until they pass off the cam abruptly, allowing the box to drop by gravity in position to be struck again. During the ascent of the 70 lifting-box the pawl is engaged with the rack on the slide, so that the ramming-cylinder is lifted; but as soon as the box has ascended sufficiently far to cause the heel of the pawl to engage the trip the toe of the pawl is 75 thrown out of engagement with the rack, whereupon the slide and rammer fall by gravity and the rammer-bits pack the sand tightly. When the rammer is again rising for another blow, the flask and pattern are turning so 80 that any parts of the mold being formed which were not properly packed by the previous blow receive a direct impact, and thus the packing pressure applied to all parts of the mold is the same. After the rammer has 85 fallen the lifting-box drops, the pawl trailing on the rack, and the next tappet presented to the cam causes a repetition of the process. The employment of hinged rammer-bits is very advantageous, because they 90 adapt themselves to the peculiar formation of the hub of the pattern and insure a proper packing or ramming of this part of the mold, otherwise difficult to obtain. With the present machine two molds can be rammed at the 95 same time, as the two sets of mechanisms are duplicates. When two molds are being rammed and one is completed before the other, the mechanism used on the completed mold is stopped by disengaging the pawl and 100 holding the lifting-box up by engaging its catch with the pivoted catch.

If desired, only one set of ramming mechanism can be used at a time, and as soon as the mold is completed the sand-box can be 105 removed and the frame swung on its pivots clear of the flask and pattern on the table. These can then be removed from the table by a crane and set on end and the pattern raised out of the mold.

Having thus described my invention, what I claim as new, and desire to secure by Letters Patent, is—

1. In a machine of the class described, the combination with a hollow cylindrical ramming device, of a plurality of hinged bits at the periphery of said device, so as to be capable of rocking or swinging laterally.
2. In a machine of the class described, the combination with a flask and a pattern therein in having a hub or head, of a mold-rammer adapted to enter the flask around the pattern, and a plurality of bits hinged to the periphery of said mold-rammer and adapted to rock or swing laterally.
3. In a machine of the class described, the combination with a flask, and a pattern therein, of a sand-box having pins fitted in the end of the pattern and supported above the same.
4. In a machine of the class described, the combination with a flask, and a pattern therein, of a sand-box having an annular discharge-opening in its bottom, and pins on said box which are removably received in pockets in

- the end of the pattern, whereby the box is supported above the pattern.
5. In a machine of the class described, the combination with a flask, and a pattern therein, of a sand-box of approximately the diameter of the pattern, rigidly supported above the same, having a discharge-opening for delivering the sand into the flask, and a hollow ramming or packing cylinder adapted to reciprocate in and out of the flask and to receive the pattern and sand-box during its entry in the flask.
6. In a machine of the class described, the combination with a rotary flask and pattern, of a sand-box supported on the pattern and adapted to turn therewith, and a stationary agitator in the sand-box.
7. In a machine of the class described, the combination with a sand-box having a discharge-opening in its bottom, of an agitator having a horizontal cross-bar disposed adjacent the bottom, and means for accomplishing relative rotation of the sand-box and agitator.
8. In a machine of the class described, the combination with a sand-box having a discharge-opening in its bottom, of an agitator comprising a shaft, stepped in the bottom, and a horizontal cross-bar and upright braces and agitating-rods connecting the bar with the shaft, and means for accomplishing relative rotation of the sand-box and agitator.
9. In a machine of the class described, the combination with a slide having a rack, and a ramming device connected to the slide, both adapted to drop by gravity, of a movable lifting-box, a pawl on said box adapted to engage the rack, and a tappet adapted to alternately raise the box and release it so that it may fall by gravity.
10. In a machine of the class described, the combination with a slide having a rack, and a ramming device connected to the slide, both adapted to drop by gravity, of a lifting-box having a cam-track, a pawl pivoted to the box and adapted to engage the rack when the box is raised, and a tappet adapted to alternately strike and travel on the cam and raise the box, and release it.
11. In a machine of the class described, the combination with a slide having a rack, and a ramming device connected to the slide, both adapted to drop by gravity, of a lifting-box, a pawl pivoted thereto adapted to engage the rack when the box is raised, a trip adapted to engage the pawl and release it from the rack when the box has been raised a predetermined height, and means for intermittently raising the box.
12. In a machine of the class described, the combination with a slide having a rack, and a ramming device connected to the slide, both adapted to drop by gravity, of a lifting-box, a pawl pivoted thereto adapted to engage the rack, an abutment on the box for supporting the toe of the pawl, a limit device on the box for limiting the movement of the heel of the pawl, a trip adapted to engage the heel of the pawl and disengage the latter from the rack when the box has reached a predetermined height, and means for intermittently raising the box.
13. In a machine of the class described, the combination with a slide having a rack, and a ramming device connected to the slide, both adapted to drop by gravity, of a lifting-box having an inclined cam-track, a pawl for engaging the rack when the box is raised, and a tappet-wheel having tappet-arms provided with antifriction-rollers adapted to strike the cam-track and travel thereon.
14. In a machine of the class described, the combination with a slide having a rack, and a ramming device connected to the slide, both adapted to drop by gravity, of a lifting-box, means thereon for engaging the rack, means for intermittently raising the box, a catch on the box, and a movable sustaining-catch adapted to support the box out of operative position when engaged with the aforesaid catch thereon.
15. In a machine of the class described, the combination with a guide-casing having a slot in its side, of a slide movable in and guided by the casing, a rammer hung from a bracket which is connected to the slide and moving in the slot, means for automatically releasing it so that it will fall by gravity, cables connected to the slide, and weights connected to the cables which partially counterbalance the slide and rammer.
16. In a machine of the class described, the combination with a guide-casing having guides on its opposite sides and a slot in its front, of a slide movable in the casing, a rammer hung from a bracket which is connected to the slide and moves in the slot, counterbalancing-weights slidable in the guides at opposite sides of the casing, cables connecting the weights to the slide, and means for automatically raising and releasing the slide.
17. In a machine of the class described, the combination with two independent sets of ramming mechanism consisting of a slide and a rammer connected thereto, of independent windlasses, independent cables connecting the respective windlasses to the slides, and means for operating one windlass at a time or both simultaneously.
18. In a machine of the class described, the combination with two independent sets of ramming mechanism, whereby two molds may be formed simultaneously, each set comprising a gravity-rammer and automatic means for alternately lifting and releasing the same, of independent stop devices for rendering either of said automatic lifting mechanisms inoperative on the completion of the mold.
